ATTORNEY

UNITED STATES PATENT OFFICE

STANLEY E. GUNNISON, OF NEW YORK, N. Y.

COLLAPSIBLE TUBE HOLDER

Application filed May 13, 1931. Serial No. 537,023.

My invention relates to container holders and refers particularly to devices adapted to hold collapsible tubes and similar containers.

It is common custom to pack creams and pastes, such as shaving cream, tooth paste, face creams and similar products, in collapsible tubes, the contents being forced therefrom by pressing, or collapsing, the lower portion of the tube, thus causing the escape of the 10 contents from an opening in the upper end thereof.

In the absence of a holder, these tubes, when not in use, lie upon the wash-stand or upon shelves.

15 As the tubes usually carry water after use, and as frequently the outside walls of the tube are not free from their contents the surfaces upon which they rest become wet and sticky, and the tubes become contaminated 20 and unhygienic. This promiscuous placement of a plurality of tubes is not only untidy in appearance but is also liable to unhygienic results.

25 My invention overcomes all of the above and other objectionable features incident to placing such holders upon a horizontal surface, and presents a device in which the tubes are maintained in an orderly manner, easy of access, with a natural elimination of exterior moisture to a common exit, without contamination with each other and with a maintenance of hygienic condition.

35 The novelty and advantages of the device of my invention will be evident upon a consideration of my specification and accompanying drawings, in which similar parts are designated by similar numerals.

40 Figure 1 is a perspective view of one form of my device illustrating the manner in which tubes are carried therein.

Figure 2 is a top plan view of Figure 1 with the tubes removed.

45 Figure 3 is a longitudinal section through the line 3—3 of Figure 2.

Figure 4 is a cross-section through the line 4—4 of Figure 2.

Figure 5 is an end view of my device made of sheet-material.

50 Figure 6 is a section through the line 6—6 of Figure 7.

Figure 7 is an end view of a modified form of the device of my invention.

The particular form of the device of my invention shown in the accompanying drawings 55 consists of a body member 10 having a longitudinally disposed Y shaped recess 11, 12 therein, the bottom 13 of said recess being inclined with respect to the base of the body member 10. One side of the body member 10 has a plurality of holes 14, 14, into which dowel pins 15, 15, may be inserted and cemented, the extended portions of said dowel pins being inserted into and cemented within holes in a wall, for instance, in order to suspend 60 the device if desired.

65 The device shown in Figures 1 to 4 illustrate my device in which the body portion is solid, as for instance wood, metal, glass, porcelain and so forth, while the device shown in Figure 5 is made from sheet material, the body portion therefore being hollow.

70 The operation of the device is as follows:—

75 Collapsible tubes 16, 16, such as those employed to contain shaving cream, tooth paste, and other liquid or paste materials, are placed within the Y-shaped recess 11, 12, the collapsed portion of the tube being positioned within the recess 11, the inclined faces 12, 12 of the recess supporting the tube in upright position. As the contents of a tube are in 80 part removed, the empty portion of the tube is folded upon itself, as shown in Figure 4, and the holder employed as described.

85 The modified form of my device shown in Figures 6 and 7 consists of a body member having the bottom 17, the sides 18 and 19, and the ends 20 and 21. The inner face 22 of the bottom 17 is inclined downwardly and has a drain opening 23 in its lower part. The device rests upon a plurality of supports 24, 24. The inner faces of the two sides 18 and 19 form a Y-shaped space 25 for the support 90 of collapsible tubes. The operation of this modified form is similar to that previously described.

95 It will thus be seen that my device may be positioned upon a horizontal plane surface, as upon a wash-stand, or it may be suspended from a vertical surface, that it is capable of holding a number of tubes, that each tube 100

may be removed and replaced without disturbance of other tubes, that it holds tubes of different length and of different amounts of contents, that the tubes are maintained in a 5 clean condition, that the tubes are prevented from contact with each other and that moisture, or water, drained from the tubes is carried to a common exit.

While in my drawings and description, I 10 have referred only to collapsible tubes, I do not limit myself to this particular use of my device, as it is evident that it may be employed for other purposes.

I do not limit myself to the particular size, 15 shape, number, arrangement or material of parts as shown and described as these are mentioned simply as a means for clearly describing the device of my invention.

What I claim is:—

- 20 1. A collapsible tube-holder comprising a body member having an upwardly opened Y-shaped recess therein, the bottom of said recess being inclined with respect to the base of said body member.
- 25 2. A collapsible tube-holder comprising a body member having an upwardly opened Y-shaped recess therein, and means for draining liquid from within said recess.
- 30 3. A collapsible tube-holder comprising a body member having an upwardly opened Y-shaped recess therein, the bottom of said recess being inclined with respect to the base of said body member and means for draining liquid from within said recess.
- 35 4. A collapsible tube-holder comprising a body member having an upwardly and longitudinally outwardly opened Y-shaped recess therein, the bottom of said recess being inclined with respect to the base of said body member.
- 40

Signed at New York city, in the county of New York and State of New York, this 12th day of May, 1931.

STANLEY E. GUNNISON.
